UNITED STATES PATENT OFFICE.

JOHN M. STUCKER AND WILLIAM J. KAMERER, OF ROSEDALE, KANSAS.

VULCANIZING ATTACHMENT FOR INTERNAL-COMBUSTION ENGINES.

1,414,445.

Specification of Letters Patent.

Patented May 2, 1922.

Application filed September 6, 1921. Serial No. 498,760.

To all whom it may concern:

Be it known that we, JOHN M. STUCKER and WILLIAM J. KAMERER, citizens of the United States, and residents of Rosedale, 5 county of Wyandotte, State of Kansas, have invented a certain new and useful Improvement in Vulcanizing Attachments for Internal-Combustion Engines, of which the following is a complete specification.

10 This invention relates to vulcanizing attachments for internal combustion engines, and has for its object to produce a simple, cheap, light and efficient device for utilizing waste heat from a motor car engine for 15 the purpose of vulcanizing patches on inner tubes and tire casings.

A further object is to produce a device of this character which can be easily and quickly secured in or removed from position, and which will retain its position when 20 the car is in travel so that time and fuel may be conserved if desired.

With the objects named in view, the invention consists in certain novel and useful 25 features of construction and combinations of parts as hereinafter described and claimed; and in order that it may be fully understood reference is to be had to the accompanying drawing, in which:—

30 Figure 1 is a side elevation of a part of an internal combustion engine equipped with a vulcanizing attachment embodying the invention.

Figure 2 is a top plan view of the construction shown by Figure 1.

Figure 3 is a vertical cross section taken on the line III—III of Figure 1.

Figure 4 is a vertical central cross section showing the invention as equipped with 40 a casing vulcanizer of the preferred type.

Figure 5 is a detail perspective view showing the attachment with the casing vulcanizer in superposed relation to the tube vulcanizer, but with a modified form of 45 means for securing the casing vulcanizer in place.

Figure 6 is a reduced cross section taken through the construction shown by Figure 5.

In the said drawing, 1 indicates a plate 50 of sufficient length and width for vulcanizing a blow-out or the like in a tube. The upper side of the plate is smooth and flat and it is provided in its lower side, nearer one side margin than the other, with a 55 groove 2 for snugly receiving the upper part of the exhaust manifold of an internal com-

bustion engine. Near the opposite margin the plate is provided with a series of depending arms 3 having notches 4 in their lower ends, for the reception of certain of the bolts forming a part of the engine and adapted for clamping the manifold firmly in place.

F indicates the body of an engine, F is the exhaust manifold, G the intake manifold and H the bolts for securing the manifold in place in conjunction with the spanners I, the latter being mounted on the bolts and engaging the exhaust and intake manifolds, as customary.

The vulcanizer plate 1 is fitted as explained upon the exhaust manifold, with its inner edge in close proximity to the body of the engine. The clamping bolts H extend through the notches in the lower ends of arms 3 and engage the body of the engine as customary, and thus reliably secure the vulcanizing plate in such relation to the exhaust manifold that the former soon becomes heated to a temperature sufficiently 80 high for vulcanizing inner tubes. The construction is such that it will retain its position when the car is in travel and is of such light weight that it does not impose any additional burden on the engine or driving 85 mechanism of the car, it being also obvious that the vulcanizing plate can be secured in or removed from position quickly and easily.

In order that the invention may be made applicable for vulcanizing casings as well as tubes, a channeled plate 6 adapted for properly receiving sufficient area of a tire casing to cover the point where the treatment is to occur, is placed upon the plate 1. In the preferred construction, a wire 7 is pivotally 90 connected at 8 to the inner side of the plate 6, and thence extends downwardly through a notch 9 in the inner edge of the plate 1. The wire is provided at a suitable point with a retractile spring 10 and at its free end with a hook 11 for engaging a notch 12 in the outer edge of the plate 6, the construction described being shown clearly by Figure 4. By this arrangement the plate 6 can be quickly and easily clamped with the proper tension on plate 1 to hold the former firmly in position.

In the construction disclosed by Figures 5 and 6, the tire vulcanizing plate 6 is as hereinbefore stated, of modified form, that 110 is to say, it is provided with a hook 13 fitting around the outer edge of plate 1 and

underlying the same, and equipped with a clamping screw 14 for engagement with the underside of the plate.

Assuming that the engine has been operating sufficiently long to have raised the plate 1 to a vulcanizing temperature, the tube to be vulcanized is placed in deflated condition, flatly upon the plate and clamped in such position until the vulcanizing operation is completed, that is, until the raw rubber to be vulcanized is sufficiently cured and has become an integral part of the tube.

When a casing is to be vulcanized it will be secured by the customary clamp or clamps upon the plate 6, and the vulcanizing operation performed in the usual manner.

It is apparent that the invention is susceptible of other modifications in minor particulars and we therefore do not desire to restrict ourselves to the construction shown and described, but reserve the right to make such changes as properly fall within the spirit and scope of the appended claims.

We claim:

- 25 1. The combination with the exhaust manifold of an internal combustion engine, of a flat plate superposed with respect to the manifold and heated thereby through conduction and radiation, and a casing vulcanizing plate having a channelled upper face, in superposed relation to the first-named plate.
- 30 2. The combination with the exhaust manifold of an internal combustion engine, of a flat plate superposed with respect to

the manifold and heated thereby through conduction and radiation, a casing vulcanizing plate having a channelled upper face, in superposed relation to the first-named plate, and a spring clamp fitting the exhaust manifold at its underside and attached at its ends to opposite sides of the casing vulcanizing plate.

3. The combination with the exhaust manifold of an internal combustion engine, of a flat plate superposed with respect to the manifold and heated thereby through conduction and radiation, a casing vulcanizing plate having a channelled upper face, in superposed relation to the first-named plate, and a spring clamp fitting the exhaust manifold at its underside and attached at its ends to opposite sides of the casing vulcanizing plate; said attachment being permanent at one end and detachable at the other.

4. The combination with the exhaust manifold of an internal combustion engine, of a flat plate superposed with respect to the manifold and heated thereby through conduction and radiation; said plate having a longitudinal groove receiving the upper side of the exhaust manifold and notched depending legs, and bolts extending through said notches into the engine body and clamping said plate firmly in place.

In witness whereof we hereunto affix our signatures.

JOHN M. STUCKER.
WILLIAM J. KAMERER.
